APPARATUS FOR REMOVING PAPER
INSULATION FROM WIRES

Charles H. Goodyear, Carlton Hill, and Ernest J. Gruen, Carteret, N. J., assignors to Western Electric Company, Incorporated, New York, N. Y., a corporation of New York

Application April 2, 1952, Serial No. 280,134

5 Claims. (Cl. 134—64)

1

This invention relates to salvaging apparatus and more particularly to apparatus for salvaging wire and pulp from pulp insulated wire.

In the manufacture of certain types of cables for use in the telephone industries, the wires are covered with a pulp insulating material. When the cables containing the insulated wires are rejected for any reason, it is desirable to salvage the wires without causing damage thereto so that they may be re-insulated without reprocessing the metal. Further savings may be effected in this operation if the pulp is removed from the wire in such a manner that it can be collected easily and returned to the pulp preparation system to be used again to insulate other wires.

The object of this invention is an apparatus which is simple in structure and highly efficient for salvaging the wire and pulp from a pulp insulated wire.

With this and other objects in view, the invention comprises an apparatus wherein jets of water under pressure are directed toward the insulated wire as it travels longitudinally in a given path to soften the pulp and force it from the wire.

More specifically, the apparatus includes a water bath wherein the pulp may be softened on the wire as the wire is caused to travel about a series of guides in the bath. In another portion of the apparatus rollers support the insulated wire and direct it in a given path relative to a series of nozzles from which jets of water are directed to the wire under pressure to force the insulation from the wire. A die element having an aperture larger than the wire and disposed concentric therewith is positioned relative to nozzles directing jets of water through the aperture in directions opposing the direction of travel of the wire to force any remaining particles of pulp from the wire.

The pulp, when first removed from the wire, is in long stringy sections which must be disintegrated before the pulp can be used again. Suitable means, such as a perforated plate or a multiplicity of vertical wires, is therefore provided to intercept the stringy sections of pulp and retain them in the paths of the jets until they are broken up into pieces which can be readily re-processed.

Other objects and advantages will be apparent from the following detailed description when considered in conjunction with the accompanying drawings wherein:

Fig. 1 is an isometric view of the apparatus; 55

2

Fig. 2 is an isometric view of one of the units of the apparatus illustrating the doors permitting access into the interior thereof;

Fig. 3 is an enlarged vertical sectional view of the unit shown in Fig. 2, illustrating one species of the retaining means for the pulp;

Fig. 4 is an enlarged fragmentary sectional view taken along the line of 4—4 of Fig. 3;

Fig. 5 is a fragmentary sectional view taken along the line of 5—5 of Fig. 3, and

Fig. 6 is a fragmentary detailed view illustrating the other species of retaining means.

Referring now to the drawings, attention is first directed to Fig. 1 which illustrates an apparatus capable of processing two wires singly or simultaneously. The apparatus includes supports 10 for supply reels 11 including the conventional rotatable wire guides 12 and fixed positioned guides 14. A suitable tank 16 may be filled

20 with water to a given level to serve as a bath for a pulp insulated wire 17. In the present embodiment of the invention, guide units indicated generally at 18 include frames 19 pivotally mounted at 20 to the inside of the tank 16 and provided with series of grooved rollers 21 about which the wire 17 may travel. One of the units 18 is shown in its upper position where it may be held by any suitable means not shown during the threading of the wire about the various grooved rollers after which the unit may be lowered to position all of the grooved rollers beneath the surface of the water in the tank.

The wire 17 is threaded through unit 25 and onto a takeup reel 26. In the present embodiment of the invention, two reels 26 are shown removably mounted on a shaft 27, connected through a clutch 28 to a speed reducing unit 29 which has its input shaft 30 driven by a motor 31. Any suitable distributing mechanism may be employed to distribute the wire on either takeup reel 26.

Referring now to the unit 25, attention is first directed to Fig. 2 which illustrates top doors 33 and side doors 34 which may be opened for the threading of the wire through either side of the unit and for possible maintenance of the interior structure of the unit. The doors may be provided with suitable latches and also suitable sealing means if such is desired.

Attention is now directed to Fig. 3 which illustrates grooved rollers 36 and 37 for the insulated wire 17 as it enters the unit 25 through an inlet 38. A series of grooved rollers 40 are supported in a given plane to direct the insulated wire in a given path through the unit.

Sets of nozzles 41 are disposed in parallel spaced positions to direct jets of water under pressure to the insulated wire 17. The nozzles are connected through valves 42 to a pipe line 43, the valves being adjustable at 44. The line 43 extends to a pump 46 as illustrated in Fig. 1. The pump 46 is supplied with water from a supply line 47 and is driven by a motor 48.

The wire 11 after leaving the jets 41, travels around grooved pulleys 50 and 51 to its respective takeup reel 26. A die element 52 shown in Figs. 3 and 4 is mounted so that its truncated-cone shaped aperture 53 will be disposed concentric with the path of the wire travelling between the groove rollers 50 and 51. Nozzles 54, supported at 55 and connected through a flexible line 56 to the line 43 at 57, are disposed relative to each other and the element 52 to direct jets of water under pressure through the aperture guided by the contour of the aperture in directions opposing the direction of travel of the wire to remove any particle of pulp which might remain on the wire after leaving the jets from the nozzles 41.

All of this mechanism is housed in a chamber 60 of the unit 25, the doors 33 and 34 of which may be closed and latched to seal the chamber when the apparatus is in operation. The unit 25 has thus far been described as including one set of structures for processing one wire whereas as the chamber 60 in the present embodiment of the invention includes two sets of structures which are identical for processing two wires singly or simultaneously. The chamber 60, therefore, includes a central partition 61 dividing it in two equal parts open at 62 to a single drain 63 for the water and pulp. The partition completes the sealing of one side of the chamber while the other side may be opened to thread another wire therethrough.

A receptacle 65 removably supported at 66 beneath the path of the wire includes a baffle 67 at one end thereof and an outlet 68 at the opposite end thereof. The species of the invention shown in Fig. 3 includes a retaining element 70 having a multiplicity of vertically extending wires 71 which function to retain the portions of pulp removed from the wire in the path of the jets of water from the nozzles 41 until these portions have been broken up sufficiently by the jets of water to escape from between the wires 71 and travel through the outlet 68.

The species of the invention shown in Fig. 6 includes a retaining element in the form of a plate 75 mounted above the outlet 68 and having a multiplicity of apertures 76 to retain the pulp removed from the wire in the path of the jets of water from the nozzles 41 until the pulp is broken up sufficiently to pass through the apertures 76 to the outlet 68.

Considering now the operation of the apparatus, let it be assumed that a supply reel of pulp insulated wire is mounted on one of the supports 10 and threaded through the apparatus with its leading end connected to its respective takeup reel 26. To set the apparatus in operation after threading of the wire has been completed and the doors to the unit 25 closed, the motors 31 and 48 are energized, causing longitudinal advancement of the wire and forcing water under pressure through the various nozzles. With the arrangement of guides in the unit 18, the wire will travel for considerable time about the successive grooved rollers in the water bath dur-

ing which time, the pulp will be softened. The wire then travels into and through the unit 25 where it is subjected to successive jets of water under pressure adapted to force the pulp insulation from the wire. As a rule, the insulation falls away in strips of varied lengths from the wire and drops in this form onto the retaining means 70 or 75. The retaining means will hold the pulp in the path of the jets of water until it is broken up into particles sufficiently small to escape between the wires 71 or through the apertures 76. If any portion of pulp should remain on the wire after passing beyond the nozzles 41, this portion of pulp will be subjected to the die element 52 and the jets of water from the nozzles 54. The jets of water from the nozzles 54 are directed in their individual paths opposing the direction of travel of the wire, forcing the particle of insulation to travel in one direction while the wire tends to pull it in the opposite direction to sever the insulation from the wire. Furthermore, the contour of the aperture 53 is such that in one instance it will increase the driving forces of the jets of water directing them inwardly toward the path of the wire and any insulation which might remain on the wire. Furthermore, the position of the nozzles and the contour of the aperture 53 will tend to cause a swirling action of the jets of water about the wire, this swirling action increasing in momentum through the aperture to assure removal of any particle of pulp from the wire.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for salvaging the wire and pulp from pulp insulated wire comprising means to advance the insulated wire longitudinally in a given path, means to direct jets of water under pressure toward the path to remove the pulp from the wire, and means to retain the pulp in the path of the jets of water until the pulp is separated into small portions thereby.

2. An apparatus for salvaging the wire and pulp from pulp insulated wire comprising means to advance the insulated wire longitudinally in a given path, a water bath, means to cause the insulated wire to travel through the water bath to soften the pulp on the wire, and means to direct jets of water under pressure toward the path to remove the pulp from the wire.

3. An apparatus for salvaging the wire and pulp from pulp insulated wire comprising means to advance the insulated wire longitudinally in a given path, a water bath, a unit normally disposed in the bath having a series of guides for the wire to cause the wire to travel for a given period of time in the bath to soften the pulp on the wire and means to direct jets of water under pressure toward the path to remove the pulp from the wire.

4. An apparatus for salvaging the wire and pulp from pulp insulated wire comprising means to advance the insulated wire longitudinally in a given path, a water bath, a unit normally disposed in the bath having a series of guides for the wire to cause the wire to travel for a given period of time in the bath to soften the pulp on the wire, means to direct jets of water under

pressure toward the path to remove the pulp from the wire and means to swingably support the unit for movement between its normal position in the bath and a threading position outside the bath.

5. An apparatus for salvaging the wire and pulp from pulp insulated wire comprising means to advance the insulated wire longitudinally in a given path, a water bath, a unit normally disposed in the bath having a series of guides for the wire to cause the wire to travel for a given period of time in the bath to soften the pulp on the wire and means to direct water under pressure in a swirling path about and in engage-

6
ment with the wire to remove the pulp from the wire.
